RAILWAY TRACK CIRCUIT APPARATUS

Paul N. Martin, Swissvale, Pa., assignor to The Union Switch & Signal Company, Swissvale, Pa., a corporation of Pennsylvania

Application May 31, 1933, Serial No. 673,605

18 Claims. (Cl. 246—41)

My invention relates to railway track circuit apparatus, and has for an object the provision in apparatus of this character of a track relay combination which can be adjusted to provide as nearly as possible maximum shunting sensitivity under infinite ballast resistance condition. I accomplish this result by providing a track relay combination which may be adjusted to pick up and release on as nearly as possible the same values of current and voltage. Apparatus embodying my invention also provides improved shunting sensitivity under all conditions, and reduces the shunting time for any value of train shunt resistance.

15 I will describe several forms of apparatus embodying my invention, and will then point out the novel features thereof in claims.

In the accompanying drawings, Fig. 1 is a diagrammatic view showing one form of track circuit apparatus embodying my invention. Figs. 2, 3, 4, 5, and 6 are views similar to Fig. 1, but each showing a modified form of relay combination also embodying my invention.

Similar reference characters refer to similar parts in each of the views.

Referring first to Fig. 1, the reference characters 1 and 1^a designate the track rails of a railway track, which rails are divided by insulated joints 2 to form a track section A—B. A source of current C is connected across the rails at one end of this section through a current-limiting resistor 3, this source, as here shown, being a battery. Located at the other end 35 of the section is a primary relay P and a secondary relay S. The primary relay P is provided with a pick-up circuit which is connected across the rails 1 and 1^a, which circuit passes from rail 1, through the entire operating winding 40 13 of relay P, and the back point of contact 6 of relay S to rail 1^a. Relay P is also provided with a holding circuit which passes from rail 1, through a portion of the operating winding 13 to a tap 16, and then through a resistor 9 and the 45 front point of contact 6 of relay S to rail 1^a. Contact 6 is a continuity transfer contact, meaning that when the relay S closes, the front point of contact 6 closes before the back point of this contact opens. It will be seen from the foregoing 50 that the pick-up circuit for relay P includes the entire operating winding of this relay, whereas the holding circuit includes only a portion of the operating winding and a resistance 9 which compensates for the reduced resistance of the relay 55 winding. The secondary relay S is provided with

a circuit which includes a battery 12 and a front contact 5 of relay P.

The primary relay P is preferably a relatively low resistance relay having normal pick-up and release characteristics, and may, for example, be a 4-ohm track relay. The secondary relay S is preferably a relatively high resistance relay having slow pick-up characteristics, and may, for example, be a 50-ohm relay. Relay S is provided with additional contacts, such as 7 and 8, which may be used to control circuits for signals or any other desired traffic governing apparatus.

The operation of the apparatus shown in Fig. 1, is as follows: Normally both relays P and S are closed, so that the holding circuit for relay P is connected across the rails of section A—B. The resistor 3 is adjusted to substantially the same value as it would be for an ordinary track relay having the same resistance and working current as relay P with its full winding 13. Then when a train enters this section, the shunt across the rails formed by the wheels and axles causes relay P to release very rapidly because only a portion of the winding of this relay is connected across the rails. After a time interval determined by the slow releasing characteristic of relay S, the latter relay will also release, thereby closing the pick-up circuit for relay P across the track rails, but as long as any portion of the train occupies section A—B, the voltage across winding 13 will be less than the pick-up voltage of relay P. When the entire train leaves section A—B, the voltage across winding 13 will rise above the pick-up value of relay P, so that this relay will close. Relay S will then close, thereby opening the pick-up circuit for relay P and closing the holding circuit for the latter relay.

If the train is of light weight and conditions are such that it provides a high shunting resistance (within limits of course), it will still cause relay P to release whereas an ordinary track relay would remain in the picked-up position. If the resistance of the train shunt varies intermittently, the primary relay P may pick up and release, following the variations in train shunt resistance, without allowing relay S to pick up.

The number of turns in winding 13 that can be cut out when the holding circuit for relay P is closed, is determined chiefly by the ratio of the release value of this relay to its pick-up value. When relay P is a standard track relay, in so far as the resistance of its winding is concerned, approximately 25% of the total turns of winding 13 can be cut out, provided that the value of resistor 9 is substantially equal to the resistance of the 55

turns which are cut out. The parts may be so proportioned that both the release current and the release voltage of the relay combination are made to approach the pick-up current and the 5 pick-up voltage, respectively, so that the relay combination produces the maximum shunting sensitivity obtainable with a track circuit of any length.

Referring now to Fig. 2, the apparatus shown 10 in this view is the same as that shown in Fig. 1, except that a front contact 4 of relay P is included in the holding circuit for this relay. The operation and characteristics of this form of the apparatus are similar to those of the apparatus 15 shown in Fig. 1 with the exception that the inclusion of contact 4 in the holding circuit for relay P guarantees the release of relay S and prevents pickup of relay P over its own holding circuit. That is, once contact 4 opens, a release of 20 relay S is insured because relay P will have no energizing circuit until such time as back contact 6 of relay S closes.

Referring now to Fig. 3, the apparatus shown in 25 this view is the same as that shown in Fig. 1, except that the holding circuit for relay P is connected directly across the track rails 1 and 1^a, and does not include a front point 6 of the secondary relay S. This eliminates the necessity for 30 making contact 6 a continuity transfer contact. For convenience of illustration, the winding of relay P is illustrated in the form of two coils 13^a and 13^b, corresponding to the two coils of the usual electromagnet. The pick-up circuit for 35 relay P includes the entire winding of this relay as before and also the back point of contact 6 of relay S, whereas the holding circuit includes only the left-hand coil 13^a and the lower part of the right-hand coil 13^b.

In Fig. 4 the apparatus is the same as in Fig. 3, 40 except that the holding circuit includes a front contact 4 of relay P as in Fig. 2.

With the apparatus shown in Figs. 3 and 4, and especially with that shown in Fig. 3, it is advantageous for the resistance of that part of coil 13^b 45 which is cut out when relay S picks up to be as large as possible, thereby allowing the battery resistor 3 (Fig. 1) to be the same or nearly the same as it would be for the apparatus shown in Figs. 1 and 2. This may be accomplished by the 50 arrangement of connections shown in Fig. 5, wherein the lower end of coil 13^a is connected with the lower end of coil 13^b through back contact 6, and the resistor 9 is connected between the lower end of coil 13^a and the point 16 in coil 13^b. In 55 Figs. 3 and 4, the higher resistance turns or "outside" turns which are cut out when relay S picks up are located in the upper half of coil 13^b, as viewed in the drawings. In Figs. 5 and 6, the outside turns are located in the lower half of coil 13^b.

The apparatus shown in Fig. 6 is the same as 60 that shown in Fig. 5, except that the holding circuit for relay P includes a front contact 4 of this relay as in Figs. 2 and 4.

Although I have herein shown and described 65 only a few forms of track circuit apparatus embodying my invention, it is understood that various changes and modifications may be made therein within the scope of the appended claims without departing from the spirit and scope of my 70 invention.

Having thus described my invention, what I 75 claim is:

1. In combination with a section of railway 78 track and a source of current connected across the rails of said section, a primary relay and a

secondary relay, a pickup circuit for said primary relay connected across the rails of said section and including a back contact of said secondary relay as well as the entire operating winding of the primary relay, a holding circuit for said primary relay connected across the rails of said section and including a front contact of said secondary relay and a front contact of said primary relay as well as only a portion of the operating winding of the primary relay and a resistance, and a 10 circuit for said secondary relay including a front contact of said primary relay and a source of current. 5

2. In combination with a section of railway 15 track and a source of current connected across the rails of said section, a primary relay and a secondary relay, a pick-up circuit for said primary relay connected across the rails of said section and including a back contact of said secondary relay as well as the entire operating winding of the primary relay, a holding circuit for said primary relay connected across the rails of said section and including a front contact of said primary relay as well as only a portion of the operating winding of the primary relay and a resistance, and a 20 circuit for said secondary relay including a front contact of said primary relay and a source of current. 25

3. In combination with a section of railway 30 track and a source of current connected across the rails of said section, a primary relay and a secondary relay, a pick-up circuit for said primary relay connected across the rails of said section and including a back contact of said secondary relay as well as the entire operating winding 35 of the primary relay, a shunt path around said back contact and a portion of said operating winding and including a resistance whereby a holding circuit for said primary relay is provided 40 which excludes said winding portion and includes said resistance, the portion of the winding of the primary relay which is not included in said holding circuit being outside turns of one of the coils of the primary relay, and a circuit for 45 said secondary relay including a front contact of said primary relay and a source of current. 50

4. In combination with a section of railway 55 track and a source of current connected across the rails of said section, a primary relay and a secondary relay, a pick-up circuit for said primary relay connected across the rails of said section and including a back contact of said secondary relay as well as the entire operating winding of the primary relay, a holding circuit for said primary relay connected across the rails of said section and including a front contact of said primary relay as well as only a portion of the operating winding of the primary relay and a resistance, the portion of the primary 60 relay winding which is not included in said holding circuit being outside turns of one of the coils of the primary relay, and a circuit for said secondary relay including a front contact of said primary relay and a source of current. 65

5. In combination with a section of railway 70 track and a source of current connected across the rails of said section, a primary relay and a secondary relay, a pickup circuit for said primary relay connected across the rails of said section and including a back contact of said secondary relay as well as the entire operating winding of the primary relay, a shunt path around said back contact and a portion of said operating winding and including a resistance 75

whereby a holding circuit for said primary relay is provided which excludes said winding portion and includes said resistance, the portion of the winding of the primary relay which is not included in said holding circuit comprising turns of relatively high resistance per turn for decreasing the power consumed from said source and for increasing the shunting sensitivity of said track section, and a circuit for said secondary relay including a front contact of said primary relay and a source of current.

6. In combination with a section of railway track and a source of current connected across the rails of said section, a primary relay and a secondary relay, a pickup circuit for said primary relay connected across the rails of said section and including a back contact of said secondary relay as well as the entire operating winding of the primary relay, a holding circuit for said primary relay connected across the rails of said section and including a front contact of said secondary relay and a front contact of said primary relay as well as only a portion of the operating winding of the primary relay, and a circuit for said secondary relay including a front contact of said primary relay and a source of current.

7. In combination with a section of railway track and a source of current connected across the rails of said section, a primary relay and a secondary relay, a pickup circuit for said primary relay connected across the rails of said section and including a back contact of said secondary relay as well as the entire operating winding of the primary relay, a holding circuit for said primary relay connected across the rails of said section and including a front contact of said primary relay as well as only a portion of the operating winding of the primary relay, and a circuit for said secondary relay including a front contact of said primary relay and a source of current.

8. In combination with a section of railway track and a source of current connected across the rails of said section, a primary relay and a secondary relay, a pickup circuit for said primary relay connected across the rails of said section and including the back contact of said secondary relay as well as the entire operating winding of the primary relay, a shunt path around said back contact and a portion of said operating winding whereby a holding circuit for said primary relay is provided which excludes said winding portion, a portion of the winding of the primary relay which is not included in said holding circuit comprising turns of relatively high resistance per turn for decreasing the power consumed from said source and for increasing the shunting sensitivity of said track section, and a circuit for said secondary relay including a front contact of said primary relay and a source of current.

9. In combination with a section of railway track and a source of current connected across the rails of said section, a primary relay receiving energy from said rails, a secondary relay, means including a back contact of said secondary relay for supplying pickup energy to said primary relay, means including a front contact of said primary relay for supplying holding energy to the primary relay, and means for energizing said secondary relay independently of said track source of current, said means including a front contact of said primary relay.

10. In combination with a section of railway track and a source of current connected across the rails of said section, a primary relay receiving energy from said rails, a secondary relay, means including a back contact of said secondary relay for supplying pickup energy to said primary relay, means including a front contact of said primary relay and an impedance for supplying holding energy to the primary relay, and means for energizing said secondary relay independently of said track source of current, said means including a front contact of said primary relay.

11. In combination with a section of railway track and a source of current connected across the rails of said section, a primary relay and a secondary relay, a pickup circuit for said primary relay connected across the rails of said section and including a back contact of said secondary relay as well as the entire operating winding of the primary relay, a constantly closed shunt path around said back contact and a portion of said operating winding and including an impedance whereby a holding circuit for said primary relay becomes effective when said secondary relay is energized and said back contact is open, said holding circuit excluding said winding portion and including said impedance, and a circuit for energizing said secondary relay including a front contact of said primary relay.

12. In combination with a section of railway track and a source of current connected across the rails of said section, a primary relay and a secondary relay, a pickup circuit for said primary relay connected across the rails of said section and including a back contact of said secondary relay as well as the entire operating winding of the primary relay, a constantly closed shunt path around said back contact and a portion of said operating winding whereby a holding circuit for said primary relay becomes effective when said secondary relay is energized and said back contact is open, said holding circuit excluding said winding portion, and a circuit for energizing said secondary relay including a front contact of said primary relay.

13. In combination with a section of railway track and a source of current connected across the rails of said section, a primary relay and a secondary relay, a pickup circuit for said primary relay connected across the rails of said section and including the back point of a continuity transfer contact of said secondary relay; a holding circuit for said primary relay connected across the rails of said section and including the front point of said continuity transfer contact, a front contact of said primary relay, and an impedance; and a circuit for energizing said secondary relay including a front contact of said primary relay.

14. In combination with a section of railway track and a source of current connected across the rails of said section, a primary relay and a secondary relay, a pickup circuit for said primary relay connected across the rails of said section and including the back point of a continuity transfer contact of said secondary relay as well as the entire operating winding of the primary relay, a holding circuit for said primary relay connected across the rails of said section and including the front point of said continuity transfer contact as well as a front contact of the primary relay and only a portion of the operating winding of said primary relay, and a circuit for energizing said secondary relay including a front contact of said primary relay.

15. In combination with a section of railway

track and a source of current connected across the rails of said section, a primary relay and a secondary relay, a pickup circuit for said primary relay connected across the rails of said section and including a back contact of said secondary relay as well as the entire operating winding of the primary relay, a holding circuit for said primary relay connected across the rails of said section and including a front contact of the primary relay as well as only a portion of the operating winding of said primary relay and an impedance, and a circuit for energizing said secondary relay including a front contact of said primary relay.

16. In combination with a section of railway track and a source of current connected across the rails of said section, a primary relay having a winding comprising two sections, a secondary relay, a pickup circuit for said primary relay connected across the rails of said section and including both sections of said winding as well as a back contact of said secondary relay interposed between said two sections, a shunt path around said back contact and a portion of the winding of one of said sections whereby a holding circuit for said primary relay is provided which excludes said winding portion, and a circuit for energizing said secondary relay including a front contact of said primary relay.

17. In combination with a section of railway track and a source of current connected across the rails of said section, a primary relay and a

secondary relay, a pickup circuit for said primary relay connected across the rails of said section and including a back contact of said secondary relay as well as the entire operating winding of said primary relay, a constantly closed holding circuit for said primary relay including a connection around a portion of said operating winding and including an impedance, said holding circuit being alone effective to maintain the primary relay picked up when said secondary relay is energized and said back contact is open, and an energizing circuit for said secondary relay including a front contact of said primary relay.

18. In combination with a section of railway track and a source of current connected across the rails of said section, a primary relay and a secondary relay, a pickup circuit for said primary relay connected across the rails of said section and including a back contact of said secondary relay as well as the entire operating winding of said primary relay, a constantly closed holding circuit for said primary relay including a connection around a portion of said operating winding, said holding circuit being alone effective to maintain the primary relay picked up when said secondary relay is energized and said back contact is open, and an energizing circuit for said secondary relay including a front contact of said primary relay.

PAUL N. MARTIN. 30.
